UNITED STATES PATENT OFFICE.

WILLIAM WALLACE HANSCOM, OF SAN FRANCISCO, CALIFORNIA.

CABLE-RAILWAY PROPULSION.

SPECIFICATION forming part of Letters Patent No. 291,698, dated January 15, 1884.

Application filed September 19, 1883. (No model.) Patented in England August 16, 1883, No. 3,927, and November 29, 1883, No. 5,690.

To all whom it may concern:

Be it known that I, WILLIAM W. HANS-
5 com, of the city and county of San Francisco, State of California, have invented an Im-
provement in the Propulsion of Cars or Trains
on Cable-Railways; and I hereby declare the
following to be a full, clear, and exact de-
scription thereof.

My invention relates to a mode of con-
10 structing and operating the permanent way
and gripping apparatus and mounting the
traveling cable and carrier-sheaves there-
for in a rail or tram way operated by a sta-
tionary power through an endless cable; and
15 it consists in the construction of the frame for
the tube and arrangements thereon for sup-
porting the carrier-sheaves, so that they may
be adjusted to suit the direction which the
cable may move in, and also for any curve
20 which may be necessary in laying the railway
through sinuous streets or roads; also, in the
construction of the gripping apparatus to op-
erate in conjunction with the adjustable
sheaves.

25 In the accompanying drawings, illustrating
my invention, Figure 1 represents an eleva-
tion of one of the frames composing the tube,
having a vertical section through the irons
forming the slot, the rails, and through one of
30 the chairs which support the rails. Fig. 2 is
a plan view of the same, showing a hori-
zontal section through one of the chairs and the
rails which it supports. Figs. 3 and 4 are en-
larged views of the grip which operates with
35 the carrier-sheaves and frame for carrying
them, Fig. 5 being a longitudinal vertical sec-
tion, Fig. 6 being a longitudinal sectional
plan, and Fig. 7 a cross-section, showing an
end view of the frame D and carrier-sheave C
40 in an inclined position for a curved portion of
the road, the positions in Figs. 5 and 6 be-
ing vertical for a straight part of the road, it
being obvious that the sheave may be inclined
in either direction to suit the direction in
45 which the curved road extends.

Similar parts are referred to by similar let-
ters in both sheets.

In the present method and construction of
50 passing curves with the usual construction
and arrangement of propelling apparatus, it
becomes necessary to place, at intervals along

the curved portion of the road, sheaves whose
axes are vertical, that the cable may be retained
in a proper horizontal position, and if the
road is sinuous, or has curves in both direc- 55
tions laterally, these side sheaves are neces-
sary for both sides of the rope-tube, and the
rope or cable must necessarily cross from one
side of the tube to the other in passing curves in
both directions, thereby exposing the cable to 60
whatever dirt may drop down upon it through
the slot. Where roads are constructed with
a single line of track, and both parts of the cable
lie in the same tube, it would be impossible
to use these side pulleys for both ropes, as the 65
grip would necessarily lift the rope above
them in passing curves, and this I obviate by
having a grip which is open at the bottom for
the admission and release of the cable, in con-
nection with a deeper-grooved carrier-sheave, 70
when the roads become curved, the action be-
ing to raise the cable such a slight distance
above the edge of the pulley that the cable
will drop back into its carrier-sheave before
the grip passes away from it far enough to al- 75
low the cable to fall without the groove of the
sheave.

A is the frame of the tube, made of cast-
iron, and which is cast in one with it, the ex-
tensions forming sleepers, on which are the 80
chairs G, so formed that the rails J J, when
dropped into them, can be firmly secured by in-
serting the wedge K, thereby dispensing with
bolts, and the rail being made in two parts, the
joints are arranged so that they come opposite 85
the center of another rail, thus forming practi-
cally a continuous rail, and avoid the shock or
jar usually occurring in passing over the joints.
By this construction of rail and chair the frame
can easily be placed radially with any curve 90
without any necessity of drilling or punching
holes in rails, as when they are bolted to the
chairs, and any degree of exactness desired
may be obtained in so placing the frames that
when the frames D, which support the axles of 95
the carrier-sheaves, are set in their places the
proper direction for the sheave to be in for the
guidance of the cable will be obtained. The
carrier-sheaves C, when required for curves,
will have a slightly deeper groove, and be in- 100
clined, as shown by the dotted line, and the
frame D will be oscillated along the curved

slot, and secured by the bolts designed for this purpose, holes being cast at intervals in the flange in the making of the frames, so that the frames A may be placed indiscriminately anywhere along the line of road, whether it may be straight or curved, and the carrier-sheave can be put in its place without further machine-work.

10 E E are corrugated sheets of iron extending from one frame to another, and supported by the lugs or stops F F. An opening, L, is made through the web of the frame, to allow water to run through the tube.

15 P is the semicircular portion of the frame, having holes at intervals through the flange, for bolting the frame D by means of the bolt Q. The channel-irons H H, forming the slot, are riveted to the flanges of the frame. The dotted lines I I indicate the line of the surface of the pavement, it being somewhat higher near the slot than at the rails, so that any water may run away from the slot.

20 B is the grip, with its shank a, shown in a larger scale in Figs. 3 and 4, where a a is the shank, with the lugs m m and jaws d d, one of which is movable, being hinged to the shank by the lugs n n n n, the center lug extending to and being clasped by the two lugs m' m' of the slide b.

25 30 O O O are the rollers for holding and guiding the cable when not gripped by the dies f f f f, which are removably fastened to the jaws d d, so as to be renewed when worn. Ordinarily rollers for guiding the rope are arranged with 35 springs to yield when the jaws of the grip are pressed so as to nip the cable; but in this case the rollers are arranged to pass by one another, and the flexibility of the cable will yield sufficiently to allow the jaws to come together 40 and firmly hold the rope.

Having thus described my invention, what I claim as new, and desire to secure by Letters Patent, is—

45 1. The frame A, with the lugs F, opening L, and the extensions, with the chairs G and rails J J and wedges K K, in combination with the grip B, carrying-sheave C, and frame D, sub-

stantially as described, and for the purpose set forth.

2. In a cable-railway, the frame A, having 50 the opening L and the curved surface P, with bolt-holes in the flanges, and adapted for receiving the end of an angularly-adjustable frame, D, containing a carrier-sheave, C, substantially as and for the purpose set forth. 55

3. The frame A, having the opening L and the curved surface P, with bolt-holes in the flanges adapted to receive the end of an adjustable frame, in combination with the angularly-adjustable frame D, bolt Q, and carrier-sheave C, for the purpose of inclining the carrier-sheave where the road is curved, substantially as shown and described. 60

4. The frame A, carrying the adjustable sheave C, in combination with the grip B, substantially as and for the purpose specified. 65

5. The grip B, with its rollers O O O, jaws d d, and lugs n n n n, having a bottom opening of the jaws, substantially as described.

6. In a cable-railway having an underground 70 slotted tube, the grip B, having its opening for the reception and discharge of the rope at the bottom, and having its jaws operated by a vertically-moving slide, a, through the slot of the tube, in combination with one or more adjustable inclined sheaves, C, and one or more traveling endless ropes, substantially as described and set forth. 75

7. The grip B, in combination with the angular adjustable sheave C and frame D, substantially as described, and for the purpose set forth. 80

8. The frame A, having the lugs F F, in combination with the corrugated-iron plates E E, substantially as described. 85

9. The construction and arrangement of the rails J J, in combination with the chairs G G and wedges K K, substantially as and for the purpose set forth.
